UNITED STATES PATENT OFFICE

133,215

DESIGN FOR A FLAG OR SIMILAR ARTICLE

James W. Papouleas and George Stamatello,
Brighton, Mass.

Application December 12, 1941, Serial No. 104,606

Term of patent 3½ years

To all whom it may concern:

Be it known that we, James W. Papouleas and George Stamatello, citizens of the United States, residing at Brighton, in the county of Suffolk and State of Massachusetts, have invented a new, original, and ornamental Design for a Flag or Similar Article, of which the following is a specification, reference being had to the accompanying drawing, forming part thereof.

The drawing is an elevational view of a flag or similar article showing our new design.

We claim:

The ornamental design for a flag or similar article, substantially as shown.

JAMES W. PAPOULEAS.
GEORGE STAMATELLO.
